UNITED STATES PATENT OFFICE.

GABRIEL ROBERGEL, OF VINCENNES, FRANCE.

DISTRIBUTOR FOR SLENDER ARTICLES OF ELONGATED SHAPE.

Application filed March 21, 1927, Serial No. 177,195, and in France March 22, 1926.

The present invention relates to apparatus intended for the distribution singly of slender articles of elongated shape, and relates more particularly to such apparatus in 5 which a store of articles is enclosed in a magazine, the bottom of which slopes towards a passage from which there emerges a rod adapted to slide in line with the axis of the magazine and presenting at its top a 10 seat for the extremity of one of the articles to be distributed.

The article coming in contact with the rod is lifted by the latter and its free end presently encounters the cover or lid of the magazine, the walls of which cover converge gradually into an orifice towards which the article to be distributed is thus progressively directed, being finally caused to project externally through this orifice, which is just sufficiently large for the passage of one of the 20 articles.

When distributors of this type are utilized for needles, pins and other pointed articles, their operation leaves much to be desired. 25 It often happens in practice that the points of two or more articles lodge simultaneously in the cavity provided at the top of the sliding rod. This is particularly frequent when the articles inside the magazine form a considerable angle between them. It follows that 30 there is a jambing of the apparatus, and if force is applied even slightly or unconsciously upon the rod, with the intention of putting an end to this jambing, there is a likelihood of injuring the apparatus or breaking the articles engaged by the sliding rod. It is not feasible to obviate such jambing of the articles by enlarging the orifice in the cover sufficiently to allow the passage of the maximum 35 number of articles which the rod can possibly engage, for the apparatus would then fail in its main object, which is to distribute the articles singly, in particular, for the purpose of preserving them from handling up to the moment when each of them is to be utilized.

According to this invention, these drawbacks are obviated by mounting the sliding rod in such a manner that it can yield elastically as soon as the thrust imposed upon it tends to become excessive.

In these conditions, the apparatus can no longer become jammed and when the rod engages two articles simultaneously, there simply occurs a failure to distribute the article, and nothing more.

In order to facilitate the grasping of the article distributed and in order to maintain the apparatus in position of rest, the magazine is subjected to the action of a spring 60 which tends constantly to return the cover as near as possible to the end of the distribution rod.

The annexed drawing represents by way of example one of the forms of construction of 65 a distributor according to the invention.

Figure 1 is a view in elevation of the apparatus in the condition of rest.

Figure 2 is a section of the foregoing upon a vertical plane II—II of Figure 1. 70

Figure 3 is an elevation of the apparatus during the first phase of the distribution.

Figure 4 is a corresponding section upon the vertical plane IV—IV of Figure 3.

The magazine *a* is constituted by a tube, 75 which carries at its upper end a screwed cover *b* in the form of a gland, pierced at its apex with the distributing orifice. The magazine *a* receives at its base a cylindrical boss occupying the centre of a piston *c*, this 80 boss comprising a cavity *c*¹ in the shape of an inverted cone followed by a narrow axial passage passing through the piston. The latter works in a socket *d* of larger diameter than the magazine *a* but narrowed at its upper end in such a way as to form a guide for this magazine. A spring *e* located between the magazine and its socket abuts at one end against the constricted portion of this latter and at the other end against the projecting 90 rim portion of the piston *c*. This spring tends constantly to return the magazine into its socket, until the piston *c* abuts against a false bottom *f* inside this socket. The false bottom *f* is traversed at its centre by the distributing rod *g* constituted in this instance by a hair-like tube made of metal, that is a tube with a very fine orifice forming a seat at its upper end. This rod is provided at its base with a head which presses upon a piston *h* 100 adapted to slide in the socket *d* by compressing a weak spring *i* abutting against a plug *k* closing the lower end of the socket. 95

The exterior diameter of the rod *g* is preferably slightly greater than that of one of the 105 articles to be distributed. In the example illustrated these articles are needles A.

Operation.—In order to extract a needle from the distributor the cover *b* is pulled out while holding back the socket *a*, in such a 110 way as to draw out the magazine to the end of its stroke (Figure 3). The point of the

hollow cone c^1 upon the piston c is then brought towards the top of the rod g (Figure 4).

Thereafter, by allowing the magazine to return under the action of the spring e , this magazine redescends with its contents, except for one needle the point of which has become engaged in the bore of and forming a seat on the end of the rod g . This needle is held fast with relation to the magazine, and its head is encountered by the cover of the latter which gradually brings it towards the exit orifice. Finally, when the magazine has returned to its position of rest, the needle held up by the rod g emerges from the apparatus (Figure 2) and remains in this position when the magazine is released, so that it can be readily grasped.

If it happens that in one of the movements of the magazine, the bore of the rod g forming the seat at the end of such rod encounters the points of two needles at once, the spring i yields as soon as the force exerted upon the rod g exceeds the very limited power of this spring. The rod g then moves down through the false bottom f in unison with the movement of the magazine. The stroke H of the piston h (Figure 2) is at least equal to the length by which the needle protrudes from the hole in the cover b in the lowered position of the magazine.

It is therefore impossible for jamming to take place on the downward stroke of this magazine and the consequences of such jamming are automatically obviated without requiring special attention on the part of the person utilizing the distributor.

It is quite evident that the invention is not limited to the shapes and details of construction described and represented but that it may give rise to modifications. Moreover the apparatus forming the subject of the invention can be utilized not only for the distribution of needles or pins but may serve in general for the distribution of any slender objects whether of pointed or other shape.

What I claim is:

1. In a device of the character described, the combination with a socket one end of which is closed, of a member adapted for sliding in said socket, spring means between said member and the closed end of the socket, a rod carried by the said member, a seat at the

end of said rod, a movable receptacle the bottom of which slopes toward a passage for the said rod, and a bulged and pierced lid on the said receptacle.

2. In a device of the character described, the combination with a socket one end of which is closed, of a member adapted for sliding in said socket, means in the socket adapted for limiting the course of said member, spring means between said member and the closed end of the socket, a rod carried by the said member, a seat at the end of said rod, a movable receptacle the bottom of which slopes toward a passage for the said rod, and a bulged and pierced lid on the said receptacle.

3. In a device of the character described, the combination with a socket one end of which is closed, of a member adapted for sliding in said socket, spring means between said member and the closed end of the socket, a rod carried by the said member, a seat at the end of said rod, a receptacle slidably engaged in said socket and the bottom of which receptacle slopes toward a passage for the said rod, and a bulged and pierced lid on the said receptacle.

4. In a device of the character described, the combination with a socket one end of which is closed, of a member adapted for sliding in said socket, spring means between said member and the closed end of the socket, a rod carried by the said member, a seat at the end of said rod, a receptacle slidably engaged in said socket, and the bottom of which slopes toward a passage for the said rod, spring means between said receptacle and the socket, and a bulged and pierced lid on the said receptacle.

5. In a device of the character described, the combination with a socket one end of which is closed, of a member adapted for sliding in said socket, spring means between said member and the closed end of the socket, a hair-like tube carried by the said member, a movable receptacle the bottom of which slopes toward a passage for the said hair-like tube, and a bulged and pierced lid on the said receptacle.

In testimony whereof I have signed my name to this specification.

GABRIEL ROBERGEL.
